(57) **CLAIM**

The ornamental design for an air duster, as shown and described.

DESCRIPTION

FIG. 1 is a front perspective view of an air duster, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 2;

FIG. 10 is a front perspective view of another embodiment thereof;

FIG. 11 is a rear perspective view thereof of another embodiment thereof;

FIG. 12 is a front view thereof of another embodiment thereof;

FIG. 13 is a rear view thereof of another embodiment thereof;

FIG. 14 is a left side view thereof of another embodiment thereof;

FIG. 15 is a right side view thereof of another embodiment thereof;

FIG. 16 is a top view thereof of another embodiment thereof;

FIG. 17 is a bottom view thereof of another embodiment thereof; and,

FIG. 18 is an enlarged detail view of area 18 in FIG. 11.

The broken lines in the drawings illustrate the portions of the air duster, which form no part of the claimed design.

The dash-dot-dash broken lines encircling the enlarged views are for annotative purposes only and form no part of the claim thereof.

1 Claim, 18 Drawing Sheets
